UNITED STATES PATENT OFFICE.

WILLIAM HILL COOPER, OF AMSTERDAM, AND CHARLES H. COLLINS, OF ALBANY, NEW YORK, ASSIGNORS TO S. SANFORD & SONS, INC., OF AMSTERDAM, NEW YORK, A CORPORATION OF NEW YORK.

TAPESTRY-LOOM.

1,265,616.

Specification of Letters Patent.

Patented May 7, 1918.

Application filed July 24, 1916. Serial No. 110,902.

To all whom it may concern:

Be it known that we, WILLIAM H. COOPER and CHARLES H. COLLINS, each a citizen of the United States of America, the said WILLIAM H. COOPER residing at Amsterdam, in the county of Montgomery and State of New York, and the said CHARLES H. COLLINS residing at Albany, in the county of Albany and State of New York, have invented certain new and useful Improvements in Tapestry-Looms, of which the following is a specification.

Our invention relates to tapestry looms, and the object of our invention is to provide an improvement in tapestry weaving looms, whereby the border yarn and body yarn may be woven into the tapestry together with the jute and pile threads, and means for causing either the border yarn or the body yarn to be exposed or buried as desired in order to form the proper pattern or design of the woven tapestry; together with such other elements and combinations as are hereinafter more particularly set forth and claimed.

We accomplish these objects by means of the mechanism illustrated in the accompanying drawings, in which:

Figure 1 is a side elevation of a tapestry loom, partly in section, provided with our invention.

Fig. 2 is a perspective view, partly in elevation, showing the means for operating the heddle frames.

Fig. 3 is a side elevation showing the position of the yarns and heddle frames during the first cycle when the border yarn is brought to the surface.

Fig. 4 is a side elevation of the heddle frames, showing the position of the yarns during the second cycle, when the body yarn is brought to the surface.

Fig. 5 is a side elevation of the heddle frames, showing the yarn when a different tapestry is being made from that shown in Figs. 3 and 4.

Fig. 6 is a perspective view, with parts broken away, of the tapestry in course of manufacture, showing the first and second cycles.

Fig. 7 is a perspective view of a rug, showing the outline thereof.

Similar letters refer to similar parts throughout the several views.

55 In the manufacture of tapestry Brussels

carpets and rugs, the present process is to wind the plain worsted yarn onto large drums varying from five to eighteen feet in diameter. Each drum when filled with the plain or worsted yarn represents one thread 60 in the pattern or design running lengthwise of the rug. A great number of drums, by this process, have to be printed and every one differently to complete the design. The printing of these yarns or threads is a long, 65 tedious and expensive operation. After the yarn is printed it is taken off the drum, steamed, washed and dried, all requiring separate operations. The long printed skeins of yarns are then wound on small spools and 70 taken to a machine called a setting frame. Each individual spool placed on said setting frame represents one thread of the design, and the different processes through which the yarn is to go after being printed causes 75 the different threads to come at different lengths. This difference in length is caused by their not drying alike, or the drums are not exactly of the same size, or the yarn may be stretched by being spooled before being 80 printed; and sometimes the chemicals affect the length of the yarn. In the practice of this well-known process in order to get the design properly, it is set on a machine called a setting frame. Each thread is brought 85 to its proper position and clamped, all of which requires time and attention and adds to the cost of the fabric.

One very popular rug is that which is shown in outline in Fig. 7, which is usually 90 9x12 feet and has for its center, M, some solid color, with the border, L, of a darker shade running all around it.

It is a very simple matter to get the desired effect with dyed yarn so far as the 95 design is concerned, running lengthwise of the portion, L', L', as all it would be necessary to do would be to wind the plain colors onto the large beam with the threads placed in their proper order. The beam will then 100 be filled without any more labor. But on account of the dark border or band, L, running crosswise of the design, it is necessary to put the dyed yarn through the exact operation it would require if the yarn were of white or 105 plain threads. This would mean the drum printing and pattern setting operations.

By our invention applied to a tapestry Brussels loom, we are able to make a perfectly designed fabric which has the appearance of 110

body Brussels or Axminster goods in which we use all dyed yarn instead of printed yarn, which makes a better fabric at a much reduced cost of manufacture.

- 5 We perform this operation by weaving into the carpet or rug, as it is being manufactured, those yarns which go to make up the border and cause them to appear on the surface and bury the body yarn and at the same time weave into the carpet or rug the body yarns, bringing them, the body yarns, to the surface and burying the border yarns, when that part of the rug, which will be the central portion, is being woven.
- 10 15 This makes a very strong, serviceable rug, no part of which is liable to be affected by shrinking or otherwise from causes growing out of the old method of procedure as hereinbefore set forth.
- 20 25 We will now proceed to describe our invention, referring to the several figures.

In Fig. 1 we show the frame, A, of the machine provided with the beam, B, carrying the border yarn; the beam, C, carrying the body yarn; the beam, D, carrying the jute, and the double beam, E, which carries a double chain of cotton yarn. F, is a spike roller and G, the take-up roll. We provide five heddle frames. 10, is the body yarn heddle; 11, is the border yarn heddle; 12, is the jute heddle; 13, is one of the cotton yarn heddles, and 14, is the other cotton yarn heddle. H, is the pile wire, and J, is a shuttle. K is a reed.

30 35 In order to produce a rug such as that shown in Fig. 7, we must have the border yarn brought to the surface along the border, L', L', of the rug, and the body yarn brought to the surface along the portion, M, of the rug, and at the same time we may wish to weave into the rug the body yarn, jute and cotton chain as well as the border yarn.

We will now proceed to describe the manner of weaving the rug shown in Figs. 6 and 7.

In the first pick, the position of the heddles, pile wire, shuttle and yarns is shown at the left of Fig. 3 and also at the left of Fig. 6. The border yarn, N, from the beam, B, passes through the aperture in the border yarn heddle frame, 11, and over the pile wire, H. The body yarn, O, is buried beside the jute, P, and while the shuttle, J, is beneath both the jute and body yarn, one of the cotton yarns, a, is beneath the filling thread, b, and the other cotton yarn, c, is above the filling thread, b. This makes up the first pick.

60 65 The second pick is shown next to the right of the first in Fig. 3. When the border yarn, N, and the body yarn, O, are buried, one of the cotton yarns, a, is below the filling thread and the other yarn, c, is above. Between the second and third picks the yarns, a and c,

cross; the yarn, a, is raised above the filling thread and c is below, the other threads remain the same.

The fourth pick, at the extreme right of Fig. 3, is just the same as the first pick. 70 Now again the border yarn is looped above the surface. This completes the first or border yarn cycle, and is repeated as many times as is necessary in order to form the border according to the plan or design. 75

In Fig. 4, we show the body yarn cycle. In the first pick, in which the body yarn heddle, 10, is raised so as to form a loop, O, the pile wire, H, passes under the body yarn, O, making the loop. The border yarn, 80 N, side by side with the jute, P, and the cotton yarns are woven into the filling as in the case first above described.

The second pick and third pick are just the same as the second and third picks of 85 the border yarn cycle. In the fourth pick the body yarn is looped again so that the heddle, 10, is raised the same as in the first pick of the second or body yarn cycle.

It will be noted that there is a difference 90 in the height to which the heddles are raised in making our rug. When it is necessary to make the loop, as in the first and fourth picks, of each of the border and body yarn cycles, we raise the heddle carrying the yarn 95 which it is desired to loop to the highest point; then, at the same time, we weave in the jute one of the cotton yarns together with either the body or border yarn,—the one which we wish buried,—at a medium 100 height of their heddles, respectively, while the other cotton yarn heddle is down at the lowest position.

In Fig. 2, we show the device which is an important part of our invention for thus 105 providing for the proper position of the heddles. To the heddle, 10, is attached the rod, f, connected with the lever, g, fulcrumed at h. The lever, g, is attached to the rod, j. The end of this rod is adapted to 110 reciprocate in a slot, k, and housing, R, attached to the cam lever, S. The opposite end of the heddle, 11, is connected with the rod, f', which is connected to the lever, g', fulcrumed at h', which is connected with 115 the rod, j', which is adapted to reciprocate in the opening, k', in said housing, R.

The border yarn heddle, 11, has connected with it a rod, 20, which is connected with a lever, 21, fulcrumed at h, which lever is 120 connected with a rod, 22, adapted to reciprocate in an opening, 23, in the housing, 24, on the cam lever, T; while the other end of the heddle, 11, is connected with the rod, 25, which is connected to the lever, 26, 125 which is fulcrumed at h', to the end of which is connected the rod, 27, which reciprocates in the opening, 28, in the housing, 24. The cam levers, S and T, engage the cam wheels, Y and Z, mounted on the cam 130

shaft, X. On each of the cam levers, we provide a hand-operated locking hook, V, adapted to engage with a locking lug, p, one of which is on the rod, 22, and the other 5 on the rod, j. When we wish to raise the heddle, 11, to its highest position, we lock the hook, V, over the lug, p, on the rod, 22, and when the cam wheel, Z, is in the position shown in Fig. 2, the lever, 10, T, being depressed, the lug holding the end of the rod 22, to its extreme inserted position in the housing, 24, will rock the lever, 21, on its fulcrum, h, and draw the heddle, 11, to its highest position. The heddle, 10, 15 is not raised to its highest position since the hook, V, thereon is out of engagement with the lug, p, and the housing will move on the rod, j', causing the rod to operate the lever, g, only far enough to raise heddle, 20 10, to its intermediate position. There may be placed a pin, 90, against which the hook, V, will engage when in the locked position, holding the hook in place, and a pin, 95, to keep the hook from falling when out of 25 engagement with the locking lug, p. The tendency of the heddles, 10 and 11, to fall to the lowest point in the shed when the hooks, V, are unlocked is overcome by the threads passing through the heddles which 30 tend to support them; but to form a more substantial prevention we may place a bolt or pin, 98, projecting from the frame a sufficient distance to enter the path of movement of the levers, 21, and g, and thus act 35 as a stop limiting the downward movement of the heddles.

The heddles, 12, 13 and 14, are operated in the usual manner in carpet weaving machines.

40 When a rug similar to that shown in Fig. 7 is woven, beginning, for instance, at the left of the figure, by weaving the border, L, straight across requiring a border yarn to be brought to the surface, the weave will 45 be that shown at the left of Fig. 6 and marked "Border yarn cycle". During this weaving the position of the several heddles in the several picks is indicated in Fig. 3. After the border, L, has been woven and 50 we are to weave the border, L', body M, and border, L', the yarn from a beam containing the colors required to thus produce the border and body is woven as shown in Fig. 4, entitled "Body yarn cycle", and which is 55 illustrated also at the right of Fig. 6. Thus, if the body, M, of the rug is to be green and the borders black, the yarn on the beam for use during the body yarn cycle will be placed in the order of black, green, black.

60 We have shown in Fig. 5 the position of

the heddles and yarns for making a two-shot fabric in which in the first pick, at the left of the figure, the border yarn, N, is looped the same as in the first pick in Fig. 3.

65

In the second pick both the border and body yarns are buried and the cotton yarn is on the surface; while in the third pick, when the border yarn is looped and the jute and body yarn are on the surface, the cotton 70 yarn, a, is depressed and the cotton yarn, c, is at the surface.

It is apparent that we can arrange these yarns in any desired order; but what we especially desire to accomplish is that of 75 constructing figured rugs out of dyed yarn, making the lines of demarcation straight, without drum printing or setting the border ends.

What we claim as our invention and desire to secure by Letters Patent is:

1. In a tapestry weaving loom, a series of heddles, one through which the border yarn passes and the other through which the body yarn passes; lever and rod connections 85 with each of said border and body yarn heddles; cam operated levers; a housing carried by each of said levers; rods connected with each of said heddles, respectively, adapted to reciprocate in said housing; and 90 means for locking each of said cam levers in connection with the rod connected with its housing, substantially as described.

2. In a tapestry loom provided with one or more border yarn beams, one or more 95 body yarn beams, jute and cotton beams mounted in the usual manner; a series of heddle frames; heddles in said frames carrying the body yarn, border yarn, jute and cotton yarns; a cam shaft; cam wheels on 100 said shaft; cam levers engaging said cam wheels; means for connecting the border yarn heddle frame with the cam levers; means for connecting the body yarn heddle frame to the cam levers; said connecting 105 means being adapted to permit of the motion of the cam levers without moving the heddle frames; said connecting means provided with a lock which, when closed, causes the movement of the heddle frames under the direction of the cam levers, substantially as described.

In testimony whereof we have affixed our signatures in presence of two witnesses.

WILLIAM HILL COOPER.
CHARLES H. COLLINS.
